UNITED STATES PATENT OFFICE.

PAUL M. BUSICK, OF MEMPHIS, TENNESSEE.

BOOTH.

1,375,557.

Specification of Letters Patent. Patented Apr. 19, 1921.

Application filed August 31, 1920. Serial No. 407,179.

To all whom it may concern:

Be it known that I, PAUL M. BUSICK, a citizen of the United States, residing at Memphis, in the county of Shelby and State 5 of Tennessee, have invented certain new and useful Improvements in Booths, of which the following is a specification.

My said invention consists in certain improvements in the details of construction 10 and arrangement of parts of lunch and soft drink booths, particularly of the type intended for use in parks, amusement grounds, and along public streets and highways, whereby a booth of such a character is provided 15 which is not only attractive in appearance but is also convenient for use, means being provided for its ready closure and the locking of the closure therefor, as well as for the utilization of the closure for 20 adding to the attractiveness and lighting scheme of the booth when open, all as will be hereinafter more fully described and claimed.

Referring to the accompanying drawings, 25 which are made a part hereof and on which similar reference characters indicate similar parts,

Figure 1 is a front elevation of a booth of the character referred to showing the 30 front thereof open for a portion of its length and closed for the remainder of its length,

Fig. 2 a horizontal section through the same,

Fig. 3 a cross section on the dotted line 35 3-3 in Fig. 2,

Fig. 4 a detail view illustrating the closure locking means, and

Fig. 5 a detail view illustrating the means 40 for supporting the closure when in opened position.

The booth itself is or may be constructed of any appropriate design, although the design shown is the one that I prefer. It is 45 understood, of course, that it may be of metal or any appropriate material, although I prefer wood and have so constructed numbers of them, making them of a substantially portable character, so that they may 50 not only be built at a mill and hauled to the place where they are to be used, but may be moved conveniently from place to place as desired.

The booth preferably has an overhanging 55 top 10 to serve as a protection not only to the interior of the booth and its contents,

as against the weather, but as a protection to customers patronizing the booth. This extension projects a considerable distance beyond the normal front and ends of the 60 booth, as shown. The floor of the booth 11 likewise projects beyond the front to provide a platform on which customers may conveniently stand while patronizing the 65 booth.

Said booth is provided with a counter 12 usually of glass or marble or other sanitary material and has numerous storage compartments, cupboards, shelves, etc., for accommodation of goods, including ice 70 cream boxes 13, as shown. The booth is preferably provided with a door 14 in one end and with a series of mirrors 15 on its rear interior wall.

In the ceiling it is provided with numerous 75 electric lights 16 preferably recessed into the ceiling and a series of ventilators 17 are provided in the roof.

The closure for the front of the booth is preferably a sash 18 mounted on hinges 19, 80 the sash being filled with glass 20 which may be of any color or varieties of color desired to suit the color scheme of the booth and harmonize with the ornate design thereof. The lower edge of the sash is connected 85 by sash-cords or cables 21 with counterbalance weights 22, which are adapted to run in vertical ways 23 at the back corners of the booth. Sliding bolts 24 are adapted to engage with recesses in the edges of the 90 sash 18 and hold said sash in elevated position.

As will be observed by an examination 95 particularly of Fig. 3, the glass in the sash 18 when in opened or elevated position occupies a horizontal position immediately beneath the light bulbs 16 and serves to diffuse the light radiating therefrom to the interior of the booth. As will be readily understood, by an appropriate selection of 100 colors for the glass, the lighting effect within the booth can be modified or made to conform to any predetermined scheme so as to harmonize with the particular ornate design of any particular booth.

To the lower edge of each sash 18 I attach, by means of a hinge or eye bolt 25, a rod 26 which is adapted to project just beyond the edge of counter 12, where it is jointed to another part 27 at point 28. A 110 sliding rod 29 is mounted in appropriate supports underneath the counter and has

an eye in its outer end adapted to receive said member 27. A set screw 30 is provided for locking the sliding bolt 29. By this means, sash 18 may be locked in closed position without marring or in any way making perforations in the counter 12. When the sash is in opened position, the rods 26 and 27 lie upon the upper edge of the sash entirely out of the way.

10 Having thus fully described my said invention, what I claim as new and desire to secure by Letters Patent, is:

15 1. A booth of the character described provided with lights in the ceiling thereof and a hinged closure for the front thereof adapted, when raised, to cover said lights and serve as a light diffuser, substantially as set forth.

20 2. In a booth of the character described, lights mounted in the ceiling thereof, a closure for the front thereof hinged at its upper edge and formed in large part of light diffusing material, and means for supporting said closure in horizontal position beneath said lights, whereby it may be made to serve either as a closure for the booth or as a light diffuser, substantially as set forth.

3. A booth of the character described provided with an open front, an overhanging top, a counter and an extended floor in front of the counter, a closure for the open front composed largely of glass, lights in the ceiling of said booth, said closure being hinged at its upper edge and adapted to be swung on its hinges to serve as a closure for the booth or in a horizontal position beneath the lights to serve as a diffuser for the light, substantially as set forth.

4. In a booth of the character described formed with an open front, a counter, a closure for said front hinged at its upper edge, and a locking means attached to the lower edge thereof and extending across the counter and means beneath the counter for connecting with and securing said locking means, substantially as set forth.

In witness whereof, I have hereunto set my hand and seal at Memphis, Tennessee, this 16th day of August, A. D. nineteen hundred and twenty.

PAUL M. BUSICK. [L. S.]

Witnesses:

JOHN W. FARLEY,
F. M. BAILEY.
